(57) **CLAIM**

The ornamental design for a triangular wedge shaped tissue or wet wipe container with mounting sleeve, as shown and described.

DESCRIPTION

FIG. 1 is a left-side elevational view of a triangular wedge shaped tissue or wet wipe container with mounting sleeve; FIG. 2 is a right-side elevational view thereof; FIG. 3 is a top plan view thereof; FIG. 4 is a bottom plan view thereof; FIG. 5 is a front elevational view thereof; FIG. 6 is a rear elevational view thereof; and, FIG. 7 is a perspective view thereof.

The broken line showing of a toilet paper roll and a toilet paper roll holder in FIG. 1-7 is included for the purpose of showing environmental structure and form no part of the claimed design.
